(57) **CLAIM**

The ornamental design for a transformable desk lamp, as shown and described.

DESCRIPTION

FIG. 1 is a top perspective view of a transformable desk lamp, showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a bottom perspective view thereof;

FIG. 9 is a top perspective view showing the transformable desk lamp, in 1st configuration of use;

FIG. 10 is a top perspective view showing the transformable desk lamp, in 2nd configuration of use; and,

FIG. 11 is a top perspective view showing the transformable desk lamp, in 3rd configuration of use.

All the broken lines in the drawings depict portions of the transformable desk lamp that form no part of the claimed design.

1 Claim, 9 Drawing Sheets
